UNITED STATES PATENT OFFICE.

WILLIAM H. MANNS, OF WAYNESBORO, PENNSYLVANIA, ASSIGNOR TO FRICK COMPANY, OF WAYNESBORO, PENNSYLVANIA, A CORPORATION.

AMMONIA-CONDENSER FOR ICE-MACHINES.

1,272,286.

Specification of Letters Patent.

Patented July 9, 1918.

Application filed July 31, 1914. Serial No. 854,333.

To all whom it may concern:

Be it known that I, WILLIAM H. MANNS, a citizen of the United States, residing at Waynesboro, Franklin county, and State of Pennsylvania, have invented and discovered certain new and useful Improvements in Ammonia-Condensers for Ice-Machines, of which the following is a specification.

My said invention consists in certain improvements in the construction and arrangement of parts of ammonia condensers for ice making machines of that type belonging to the "flooded" system, whereby any type of condenser can be made to operate as a "flooded" condenser, and perfect and satisfactory results secured, all as will be herein-after more fully described and claimed.

The accompanying drawing which is made a part hereof, and on which similar reference characters indicate similar parts, shows a single coil of an ammonia condenser of the "flooded" type, illustrating my said invention.

In said drawing the portion marked A represents the tank for the cooling medium, B the ammonia gas header, and C the ammonia liquid header.

In the construction of the condenser, as many of the coils of pipe will be arranged side by side as required to form a condenser of the capacity desired. The inlet end 10 of each coil is coupled to the ammonia gas header B, and the discharge end 11 of each coil is coupled to the ammonia liquid header C. A controlling valve 12 is provided in the inlet end, and a controlling valve 13 in the discharge end. The gas header B receives the gaseous ammonia through the supply pipe b and the liquid ammonia header C discharges through a discharge pipe c.

Each coil of the condenser is preferably divided into two horizontal sections, substantially one third of the coil being above the division and two thirds below the division. Interposed in the coupling 14, joining the two adjacent pipes at the top of the lower section, is a valve 15 mounted on a stem 16 which has a screw-threaded section mounted in a screw-threaded perforation in the valve casing and projects to the outside when it is provided with a hand wheel 17 by which it may be operated and adjusted. Said valve seats against the end of horizontal pipe 20, which forms the first hori-

zontal return in the coil after the ammonia has made its initial passage across the condenser after entering pipe 10.

The gas header B and the liquid header C are on a level with each other, and both are on a level with the top of the condenser coil.

A flooded type of ammonia condenser is supposed to handle anhydrous ammonia in its liquid state only. All of the pipes are normally filled with liquid up to the gas header B. As soon as the ammonia gas comes in contact with the liquid ammonia the sensible heat from the ammonia gas is immediately absorbed and it will collapse into a liquid. The heat remaining in the ammonia liquid will be absorbed by the means of the water flowing from the tank A down over the outside of the coil. As soon as the ammonia gas comes in contact with the liquid ammonia which fills the coil, and is thus collapsed or condensed into a liquid state, its volume is reduced many times and therefore its flow through the coil should be controlled by means of an orifice the size of which can be regulated in proportion to the temperatures and pressures under which the operation exists.

In the operation of the apparatus shown, understand, of course, that the operation in one coil is duplicated in every other coil of the condenser, the gas coming from header B into pipe 10 immediately contacts with the liquid ammonia, which, under normal conditions, floods said pipe and immediately is collapsed into liquid form. The hot liquid thus formed passes along pipe 10 to the end opposite the inlet end and returns in pipe 20 from which it flows to the next pipe below in the coil. The size of the orifice in the discharge end of pipe 20 is controlled by means of the valve 15, which is adjusted to form a discharge opening of that size which will just accommodate the volume of liquid formed by the volume of gas coming into the pipe 10 and thus maintain an even and uniform pressure throughout the coil. The liquid ammonia flows back and forth through the pipes to the bottom of the coil and then passes through vertical pipe 21 to pipe 22 at the top of the coil and then flows in a downward direction through the coil until it reaches the lower pipe 23 which connects with the discharge pipe leading to the liquid ammonia header C.

from which the liquid ammonia is discharged through pipe *c*, as before stated.

By means of the valves 15, one of which is located in each individual coil in the condenser, it is possible to regulate the flow of the liquid from the top pipe 20 of the lower section into the other pipes of the coil, the discharge orifice being regulated to determine the quantity of gas that can be absorbed 10 or condensed by the small amount of liquid lying in the pipe from this point back to the gas header, and thereby regulate the flow of gas so that it will be uniform in each and every coil, and so that they will work 15 automatically and uniformly throughout the entire condenser.

By the operation of this apparatus the ammonia gas is condensed and cooled in uniform manner and finally discharged 20 through the liquid header within a few degrees of the temperature of the cooling medium or water itself, probably within from 2° to 5° of the initial temperature of said water.

Having thus fully described my said invention what I claim as new and desire to secure by Letters Patent is:

1. An ammonia condenser comprising a series of coils connected at inlet end with 30 an ammonia gas header, at the outlet end with a liquid ammonia header, said gas header and said liquid header being arranged on the same level and on a level with the top of the coil, and a valve interposed 35 in said coil near the gas inlet end adapted to regulate the orifice to a size which will take care of the flow of liquid ammonia absorbed by the liquid lying in the inlet pipe outside of said valve, substantially as set 40 forth.

2. An ammonia condenser comprising a series of condenser coils, the pipes of which extend horizontally and each of which coils is divided into two horizontal sections, an 45 ammonia gas header, an ammonia gas supply pipe leading to said header, a connection from said gas header to the upper pipe of

the lower section in each coil, a liquid ammonia header, a connection from said liquid ammonia header to the lower pipe of 50 the upper section of each coil, a liquid ammonia discharge pipe leading from said liquid ammonia header, a cold water supply above each coil, each coil being provided with a regulating valve interposed near the 55 upper end of the inlet section, whereby the orifice from one pipe to the next may be regulated as desired, substantially as set forth.

3. An ammonia condenser comprising a 60 coil of pipe, means for discharging a cooling medium over said coil, a gas inlet at one end of said coil, a liquid ammonia outlet at the other end of the coil, and a valve positioned in said coil and located at an appropriate distance from the inlet end and adapted 65 to maintain a liquid level between said valve and the inlet end of the coil and within the path of the cooling medium, substantially as set forth.

4. An ammonia condenser of the "flooded" 70 system type comprising a coil of pipe with inlet and outlet arranged approximately at or above the top thereof, the gas inlet being at one end of said coil and the liquid ammonia outlet at the other end of said coil, controlling valves for said inlets and outlets, a valve positioned in the coil at a 75 distance from the gas inlet and arranged whereby the size of the orifice may be regulated to conform with the volume of gas and maintain a flooded condition in the coil at uniform pressure, and means for discharging a cooling medium over said coil, substantially as set forth.

In witness whereof, I have hereunto set my hand and seal at Waynesboro, Pennsylvania, this 27th day of July, A. D. nineteen hundred and fourteen.

WILLIAM H. MANN. [L.S.]
